[57] CLAIM

The ornamental design for a paint roller yoke, as shown and described.

DESCRIPTION

FIG. 1 is a rear perspective view of a paint roller yoke showing my new design;

FIG. 2 is an enlarged top plan view thereof, the bottom being a mirror image;

FIG. 3 is a rear elevational view thereof;

FIG. 4 is a front elevational view thereof;

FIG. 5 is a right side elevational view thereof, the left side being a mirror image; and

FIG. 6 is a reduced front perspective view thereof.

The broken line showing of a paint roller and handle is for illustrative purposes only and forms not part of the claimed design.

FIG. 1**FIG. 2****FIG. 3****FIG. 4****FIG. 5**

FIG. 6
